UNITED STATES PATENT OFFICE.

JOSEPH L. PETITHOMME, OF OAKLAND, CALIFORNIA.

CAR-AXLE BOX.

SPECIFICATION forming part of Letters Patent No. 691,175, dated January 14, 1902.

Application filed June 30, 1898. Serial No. 684,854. (No model.)

To all whom it may concern:

Be it known that I, JOSEPH L. PETITHOMME, a citizen of the United States of America, and a resident of Oakland, in the county of Alameda and State of California, have invented 5 certain new and useful Improvements in Car-Axle Boxes, of which the following is a specification.

This invention consists of improvements relating to what is now known as the "Petithomme system" of car-axle boxes, and has particular relation to a novel lid for such boxes.

The invention has for its primary object the provision of a construction of lid which 15 is as efficient as any other heretofore made by me and possesses the additional advantage of being capable of opening wider than such other lids already in the art.

Improved details in the construction and 20 arrangement of the several parts will be apparent from the detailed description herein-after when read in connection with the accompanying drawings, forming part hereof, and the appended claims.

25 In the said drawings a preferable embodiment of the invention is delineated for the purpose of illustration, and when referring to the same like reference characters will designate corresponding parts in the several views.

30 Figure 1 is a perspective view of a portion of the box with the improved lid in position thereon. Fig. 2 is a vertical longitudinal section of Fig. 1. Fig. 3 is a side elevation showing the lid in open position. Fig. 4 is a front elevation, and Figs. 5 and 6 are detail views.

Referring more specifically to the drawings, A designates an axle-box, which, generally speaking, may be of any ordinary or preferred type.

40 B is the end of the axle, on which the box A is mounted, and B² and B³ are the bearing and key between the same, the latter being shown in Fig. 2.

The box-lid A², as stated, is constructed 45 with a view to affording a very large opening in order to give easy access to the interior of the box when inserting lubricant or lubricant-holding devices and when cleaning or repairing the same. To this end I have made the

50 hinge and spring connections of the box-lid in my present improvements as free as possible, so that the lid can be thrown wide open

as far up as is indicated in Fig. 3 of the drawings and still farther up and back, if necessary. The body of the lid is flat and made 55 in such a way that it will cover the entire front opening of the box and be seated squarely over it, as shown. Under the lid is placed a packing A⁵, similar to that described in my Patent No. 573,417, of December 15, 1896. 60 The lid is attached or hinged to the box by a bolt N, that is passed through two lugs A⁶ A⁷, formed at the upper corners of the lid itself, and through similar lugs A⁸ A⁹, formed on said box at the upper edge of the front opening thereof. The bolt N is shown in detail in Fig. 5 and, like the hinge-bolt referred to in my patent above mentioned, has a central quadrangular portion on which is slipped a holder P for a spring Q, said holder having 65 a central quadrangular hole P² to match. As represented in Fig. 2, the spring Q is a flat spring and extends lengthwise across the middle of the lid, bearing on the outer surface thereof, though it is covered by an open-ended 70 sheath A¹⁰. It is loosely set in its holder—that is to say, detachably secured thereto by its upper end, which is bent at Q² to catch on an under lip P³ of said holder. A stop A¹¹, formed at the lower edge of the lid and affording a 75 bearing for the lower end of the spring, prevents the latter from coming off after it is set in place. The holder P, as will be seen, bears upon the upper bent end of the spring Q and also on the outer surface of it through a projection P⁴, passed under the upper side of the sheath A¹⁰. An opening or cavity P⁵, of suitable shape, is left between said projection and the lip P³ to allow the spring to be attached and detached readily. At its lower 80 end the spring is bent under, as at Q³, Fig. 6, and is thus raised and kept in full contact with the projection P⁴. The lid is closed and opened with a lever made of a flat springy bar and used in connection with the hinge-bolt N and the spring Q thereto attached, the angular portion of said bolt causing said spring through its holder to work the lid either way. This lever is passed through a suitable slot made in one end of the hinge-bolt at the right-hand side of the box and has its upper end R² bent to keep it from dropping out when the lid is closed, as shown 85 in Figs. 1 and 4; but the said lever is other- 90 95 100

wise free to slide through the slot of the bolt, so that when the lid is opened it can be used to keep the same open by sliding it down through the slot and bringing it to bear 5 against one of the side ribs A^{12} of the box, as illustrated in Fig. 3. When the lid is closed, the lever R is pulled a little to one side and placed behind a stop A^{13} , provided on the right-hand side of the box. This operates to 10 keep the hinge-bolt in a fixed position and cause the spring thereto connected to exert a constant pressure on the lid. The box is thus tightly closed. The outer end of the stop A^{13} is inclined rearwardly, and the lever R is 15 therefore correspondingly twisted at R^2 to enable it to slide back of said stop easily. Another stop A^{14} is also provided on the box to prevent the lever from being pushed too far back when it is pressed either to place it behind the stop A^{13} or to disengage it therefrom. 20 At its lower end the lever R is curved, as at R^4 , to afford a convenient bearing for the hand in manipulating it.

While in the above disclosure one embodiment only of the invention has been described and illustrated, it is to be understood that many changes in the construction and operation of the several parts can be made without in the least departing from the spirit 25 of the invention.

Having thus described my invention, what I claim, and desire to secure by Letters Patent, is—

1. The combination with an axle-box, of a lid hinged thereto, a spring acting on the lid 35 to move the same in one direction, and a separate-piece holder for the spring to which the spring is attached.

2. The combination with a car-axle box, of a lid, a hinge-bolt passing through lugs on 40 the box and the lid, a detachable holder on said bolt, a spring detachably connected with said holder and bearing on the lid, and means for controlling the rotation of the hinge-bolt, substantially as described. 45

3. A car-axle box having a lid covering its front opening, a hinge-bolt made partly angular and passing through lugs on the box-lid, a loose spring extending lengthwise across the lid's outer surface, a sheath for the spring, 50 a holder engaging with the angular portion of the bolt and detachably engaging the spring at its upper end, said holder extending into the sheath, and means for controlling the rotation of the hinge-bolt, substantially as de- 55 scribed.

4. A car-axle box having a hinged lid, a spring bearing on the lid, and a detachable holder on the hinge-bolt for the spring, substantially as described. 60

Signed by me at San Francisco, California, this 20th day of May, 1898.

JOSEPH L. PETITHOMME.
